US00D763291S

(12) **United States Design Patent**
Henderson et al.(10) **Patent No.:** **US D763,291 S**
(45) **Date of Patent:** **** Aug. 9, 2016**(54) **DISPLAY SCREEN OR PORTION THEREOF
WITH GRAPHICAL USER INTERFACE**(71) Applicant: **ROCKWELL AUTOMATION
TECHNOLOGIES, INC.**, Mayfield
Heights, OH (US)(72) Inventors: **Benjamin Henderson**, Chardon, OH
(US); **Matthew R. Ericsson**, Lyndhurst,
OH (US); **Ashish Anand**, Mayfield
Heights, OH (US)(73) Assignee: **Rockwell Automation Technologies,
Inc.**, Mayfield Heights, OH (US)(**) Term: **14 Years**(21) Appl. No.: **29/512,462**(22) Filed: **Dec. 18, 2014**(51) LOC (10) Cl. **14-04**

(52) U.S. Cl.

USPC ..... **D14/486**(58) **Field of Classification Search**

USPC D14/485-495

CPC G06F 17/211; G06F 17/212

Primary Examiner — Karen E Kearney*Assistant Examiner* — Megan M Majcher Hartnett(57) **CLAIM**

What is claimed is the ornamental design for a display screen or portion thereof with graphical user interface, as shown and described.

DESCRIPTION

The sole FIGURE is a front view of a display screen or portion thereof with graphical user interface showing the new design. The broken lines represent the display screen or portion thereof and form no part of the claimed design.

1 Claim, 1 Drawing Sheet(56)
